UNITED STATES PATENT OFFICE.

SAMUEL J. WALASCHEK, OF NEW YORK, N. Y.

TABLE-TOP ATTACHMENT.

Application filed June 16, 1924. Serial No. 720,349.

To all whom it may concern:

Be it known that I, SAMUEL J. WALASCHEK, a citizen of the United States, residing at New York, in the county of New

5 York and State of New York, have invented certain new and useful Improvements in a Table-Top Attachment, of which the following is a specification.

This invention relates to new and useful 10 improvements in attachments for table tops and has for its principal object to provide a means whereby a round table top may be readily and easily converted into a substantially rectangular shaped table top.

15 A further object of the invention is to provide a table top attachment of the above mentioned character, which will enable the sides of the table top to be increased, the auxiliary table top being of such a construction as to enable the same to be readily and easily secured in position on the table top whenever it is desired to use the same.

20 A further object of the invention is to provide a table top attachment of the above mentioned character which will be simple in construction, inexpensive, strong and durable and furthermore adapted for the purposes for which it is designated.

25 Other objects and advantages of this invention will become apparent from the course of the following description.

30 In the accompanying drawing forming a part of this specification and in which like numerals designate like parts throughout the same:

35 Figure 1 is a top plan view of a table top with my attachment in position thereon.

Figure 2 is a bottom plan view thereof, and

40 Figure 3 is a sectional view taken approximately on line 3—3 of Figure 1.

45 In the drawing wherein for the purpose of illustration is shown the preferred embodiment of my invention, the numeral 1 designates the top of a table and the same is substantially round in the manner clearly illustrated in Figures 1 and 2. The periphery of the table top 1 is further provided with a beveled flange 6 in the manner clearly 50 illustrated in Figure 3.

55 For the purpose of increasing the size of the table and by changing the shape of the table top, the same will be converted into a substantially rectangular shaped table top.

55 The attachment whereby the above is accomplished comprises a substantially rec-

tangular shaped frame designated generally by the numeral 7 and the same includes the complementary sections 8 and 9 respectively which are hingedly connected together at 60 their adjacent ends in the manner clearly illustrated at 10 with reference to Figure 2 of the drawing. The sections 8 and 9 are formed in superposed laminations as is clearly shown in Figure 3.

65 The adjacent ends of the top laminations of the complementary sections 8 and 9 are each provided with a substantially semi-circular cut out portions 11 and 12 respectively which are adapted to cooperate so that the opening formed in the frame will conform to the contour of the table top 1. The bottom laminations of the complementary sections at the portions where the semi-circular cut out portions are provided are 70

75 cut away as illustrated at 13 and 14 respectively in the drawing. The feature just ascribed allow the sections 8 and 9 to be constructed in a very economical manner and to be of a very light nature in weight. The 80

85 cut outs 13 and 14 eliminate the necessity of matching up arcuate bevel edges to conform with those shown at 11 and 12. The edges of the semi-circular openings 11 and 12 are beveled on the under side for coop- 90

95 eration with the beveled peripheral edge 6 of the table top 1 in the manner clearly illustrated in Figure 3 of the drawing. This construction will enable the auxiliary frame to have its upper surface substantial- 90

ly flush with the upper surface of the round table top 1.

For the purpose of securing the frame in a rigid position on the table top when it is desired to use the same, I provide on the under side of the complementary section at predetermined points adjacent the cut out portions 13 and 14 thereof the ordinary door buttons 15. The same are so arranged as to cooperate with the bottom of the table top 1 at the edge thereof at spaced intervals. The table top 1 will lie substantially flush with the under side of the complementary sections so that the buttons 15 may engage the same and support the auxiliary 100 frame in a substantially rigid position on the table top 1 against accidental disengagement therefrom and further preventing the collapsing of the complementary sections comprising the frame.

110 For holding the auxiliary table top in a folded position when not in use upon the

ordinary table top, I provide the cooperating hooks and eyes 16 and 17 respectively on the opposite side edges of the complementary sections. This permits the attachment to be stored away without occupying much space.

The provision of a table top attachment of the above mentioned character, will enable a person to readily and easily increase 10 the size of an ordinary round table and change the shape thereof to a substantially rectangular shaped table top without altering the construction of the table in any manner. When it is not desired to use the auxiliary table top, the buttons 15 may be moved 15 out of engagement with the under side of the table top 1 and the sections which are hinged as illustrated at 10 may be swung upwardly so as to enable the frame to be 20 readily removed from the table top.

A device of the above mentioned character may be manufactured at a very low cost and will further be strong and durable, and does not require the loss of any consider-

able length of time and labor in attaching 25 the auxiliary table top on the top of the table.

While I have shown the preferred embodiment of my invention, it is to be understood that various changes in the size, shape and 30 arrangement of parts may be resorted to without departing from the spirit of the invention and the scope of the appended claim.

Having thus described the invention, what I claim is:—

In combination, a circular table top, an auxiliary top including complementary sections hinged together at their adjacent ends, each section including a pair of superposed laminations, the hinged edges of the top 40 laminations being arcuate in formation and beveled, and the same ends of the bottom lamination being of rectangular U-shape in formation, and means for securing the auxiliary top of said table top.

In testimony whereof I affix my signature.

SAMUEL J. WALASCHEK.
